FOREIGN PATENT DOCUMENTS

JP 2000-219065 8/2000

Primary Examiner—Stella M Reid*Assistant Examiner*—Mark A Goodwin(74) *Attorney, Agent, or Firm*—Sterne Kessler Goldstein & Fox P.L.C.(57) **CLAIM**

The ornamental design for a bonnet for a tractor, as shown and described.

DESCRIPTION

FIG. 1 is a right front perspective view of a bonnet for a tractor showing our new design;

FIG. 2 is a front view thereof;

FIG. 3 is a rear view thereof;

FIG. 4 is a right side view thereof;

FIG. 5 is left side view thereof;

FIG. 6 is a top plan view thereof; and,

FIG. 7 is a bottom plan view thereof.

The broken line showing of interior section of the headlight is included for the purpose of illustrating portions of the bonnet for a tractor and forms no part of the claimed design.
